UNITED STATES PATENT OFFICE.

FOSTER M. SPURR, OF MATTAPAN, MASSACHUSETTS.

PIPE ATTACHMENT.

1,320,939.

Specification of Letters Patent.

Patented Nov. 4, 1919.

Application filed November 16, 1918. Serial No. 262,814.

To all whom it may concern.

Be it known that I, FOSTER M. SPURR, a citizen of the United States, residing at Mattapan, in the county of Suffolk and State of Massachusetts, have invented new and useful Improvements in Pipe Attachments, of which the following is a specification.

The present invention relates to improvements in attachments for tobacco pipes and has for its object to provide means readily attachable to a pipe by which a supply of air may be introduced into the tobacco below the burning area thereof from outside the pipe. By thus supplying an additional amount of air the quality of the smoke may be controlled so that it will not sting or bite. Further it is possible to introduce air which has been treated with a suitable scent so that the flavor of the smoke will be varied as may be desired.

In the accompanying drawings:

Figure 1 is an elevation, and part section of a tobacco pipe having an embodiment of the present invention applied thereto.

Fig. 2 illustrates a slightly modified form of the improved attachment.

Fig. 3 is an end elevation of the attachment detached from the pipe.

Fig. 4 is a view showing the pipe bowl in section and a modified form of the attachment applied thereto.

Fig. 5 illustrates another embodiment of the invention.

Fig. 6 is a detail view of a slightly different form of attachment.

Referring to the drawings 1 designates the bowl of the pipe which may be of any suitable material and size and which communicates with the usual stem 2 at its lower end.

The attachment which constitutes the present invention comprises a tube 3 which has a hooked or bent portion near one end so that it may be hung over the upper edge of the pipe bowl with its short leg forming the inlet 4, projecting outwardly from the bowl and its relatively long leg forming the outlet 5 within the bowl.

In the form of the invention shown in Fig. 1 the main body of the attachment 3 extends close to the inner surface of the wall of the pipe bowl throughout its length and as shown the outlet 5 thereof is situated a short distance above the plane of the passage 6 in the stem of the pipe. The tube

3 may be given a slight longitudinal curvature near its inner outlet end so that said end will be deflected inwardly away from the wall of the bowl over which the tube extends. Such a construction is shown in Fig. 2 and in this form the lower end of the tube has a bevel or cut away portion 8 through which the outlet 7 opens.

In the embodiment of the invention shown in Fig. 4 a cup-like receptacle 9 is mounted on the curved portion of the tube and communicates with the interior thereof through an opening 10. This receptacle is, as shown, intended to be more or less filled with a suitable absorbent material 11, such as cotton, which may be treated with a flavoring or perfuming material so that the air drawn into the bowl through the tube 3 will convey such scent or perfume to the smoke as it enters the passage 6 of the pipe stem.

While it is preferred to arrange the attachment as shown in Figs. 1 to 4 in which the longer limb of the bent tube is within the bowl and the attachment is supported by extending across the edge of the bowl yet some of the advantages of the invention may be attained if the device is mounted in a passage formed in the stem outside of the bowl, as shown in Fig. 5. Also if desired the outlet opening of the tube may be increased by forming a bevel cut 12 on the face or portion thereof remote from the adjacent wall of the bowl as shown in Fig. 6 instead of beveling the surface 8 adjacent such wall as shown in Figs. 2 and 3.

The purpose and operation of the attachment will it is thought be readily understood from the foregoing description and the drawings. It will be seen that by the attachment a supply of fresh air will be admitted from outside the bowl to the lower portion of the interior thereof below the main body of tobacco and caused to mingle with the smoke to temper or agreeably affect the flavor and character thereof.

The attachment may be made of metal or any other suitable material, is relatively inexpensive, can be easily applied to or removed from an ordinary tobacco pipe.

Having thus described the invention what is claimed is:

1. An attachment for a tobacco pipe comprising a tube bent to adapt it to be hung on the edge of a pipe bowl, with its inlet leg outside the bowl, and its outlet leg depending within the bowl to supply air to the

interior of the pipe bowl near the lower portion of said bowl.

2. An attachment for a tobacco pipe comprising a tube bent to adapt it to be hung on the edge of a pipe bowl with its inlet leg outside of said bowl and its outlet leg depending into said bowl to supply air to

the interior of the pipe, and a cup or receptacle for a flavoring substance secured to and communicating with the tube adjacent its inlet end. 10

In testimony whereof I have hereunto set my hand.

FOSTER M. SPURR.
